UNITED STATES PATENT OFFICE.

AUGUSTE RENÉ LUCAS, OF PARIS, FRANCE.

ROLLER-SKATE.

1,261,568.

Specification of Letters Patent.

Patented Apr. 2, 1918.

Application filed September 28, 1917. Serial No. 193,740.

To all whom it may concern:

Be it known that I, AUGUSTE RENÉ LUCAS, a citizen of the Republic of France, and a resident of 64 Rue Ampère, Paris, France, 5 have invented new and useful Improvements in or Relating to Roller-Skates, of which the following is a specification.

This invention relates to improvements in roller skates, consisting of two roller 10 skates connected together so as to follow paths determined beforehand, combined with a steering device, the said roller skates comprising free wheels preventing them from moving backward, so as to offer a 15 point of support on the ground in order to impart to them an impulse for the forward movement.

The accompanying drawing shows by way 20 of example a construction according to the invention in which two skates can move only in a longitudinal parallel direction.

Figures 1 and 2 are respectively a side elevation and a plan of a first construction;

Figs. 3 and 4 are, on an enlarged scale, 25 respectively a side elevation and a bottom view of a roller skate according to the said first construction.

Figs. 5 and 6 show two modified constructions of the roller skate in side elevation.

Figs. 7 and 8 show respectively in side 30 elevation and in end view, partly in section, a third modified construction.

In the construction illustrated, two roller skates *a* can move parallel to each other in 35 the longitudinal direction on the longitudinal members of a frame *b* comprising at its rear end a loose bearing wheel *b*¹, movable about a vertical pin, and at its front end a steering wheel *b*² mounted on a control part 40 *b*³. *a*¹ are the rollers of each skate which are guided on the longitudinal members of the frame *b* by means of two rollers *a*² mounted at each end of the sole plate *a*³, above the longitudinal member, and a third 45 roller *a*⁴ is mounted on the same spindle as the roller *a*¹, under the longitudinal member (see more particularly Figs. 3 and 4). The roller *a*¹ of the skate is keyed to a spindle pivoted in two vertical brackets *a*⁵. To the 50 same spindle is keyed a ratchet wheel *a*⁶ with which a pawl *a*⁷, mounted on one of the brackets *a*⁵, is held in contact by means of a spring *a*⁸. This free wheel device enables the skate to roll on the ground when the 55 skate is traveling in the direction of the arrow (Fig. 1), but locks the roller *a*¹ when

the skate is brought back on the frame *b* by means of the foot. Thus a point of support on the ground is obtained which makes it possible to give an impulse to the apparatus. 60 In order to use the apparatus, the rider places one foot on each of the two skates *a*, and holds on to the steering part *b*³ (the feet may be attached in the usual way to the sole-plate by straps). The apparatus is started 65 by striking out with one of the skates, so as to try to bring it backward. Owing to the advance movement of the apparatus, the skate which has been used in order to communicate an impulse, remains behind. It 70 is then only necessary to bring it forward on the longitudinal member of the frame in order to use it again for causing the apparatus to advance.

It has been assumed in the foregoing that 75 each skate was provided with a free wheel device; nevertheless only one skate can be provided with a free wheel, the same skate being always used for producing an advance.

In order to make turning possible, it is 80 necessary to bring the two skates *a* into one and the same vertical plane; for the purpose of facilitating turning, more particularly in curves of a small radius, it is preferable to allow the roller *a*¹ to roll backward, in order 85 that the skate can take up its position at suitable points, according to the direction and angle of turning. It is therefore necessary to disengage at that moment the pawl *a*⁷ from the ratchet wheel *a*⁶ keyed to the 90 spindle of the roller *a*¹ of the skate, so as to render the said roller entirely loose in both directions of rotation. This disengagement of the pawl *a*⁷ is obtained in any desired manner, for instance (Fig. 5) by means of 95 a rod *c* guided through the sole-plate *a*³ of the skate, at the back, and a little sidewise of the heel and normally held raised above the tail *a*⁹ of the pawl by a spring *c*¹. By pressing the heel on the rod *c*, the latter will 100 press on the tail of the pawl *a*⁷ and disengage the latter from the ratchet wheel. In the modification shown in Fig. 6 the rod *c* when pressed by the foot, also acts on a lever *c*² pivoted under the sole-plate *a*³ and normally raised by a spring *c*³ above a lip *a*¹⁰ of the pawl, the said lever *c*² thus tipping the pawl *a*⁷ and disengaging it from the ratchet wheel (Fig. 6).

The device shown in Figs. 7 and 8, also 110 makes it possible to prevent the roller *a*¹ of the skate from rotating in the reverse di-

rection. To the spindle $\alpha\alpha$ of the roller a^1 is keyed a brake drum d concentric with the roller a^1 which is supported in the bracket a^5 by means of an eccentric trunnion d^1 (the 5 axis of which is represented by $y-y$). A band brake d^2 , one end of which carries a regulating device, is secured to the bracket a^5 at that side of the drum d which is situated in the direction of advance of the apparatus (arrow ω). As long as the apparatus advances in this direction, the roller a^1 and the trunnion d^1 remain in the position shown in full lines, but when an effort is exercised on the skate for the purpose of 10 causing the roller a^1 to roll backward, the reaction on its spindle $\alpha\alpha$ causes a movement of the eccentric d^1 about its axis $y-y$.

The spindle $\alpha\alpha$ of the roller a^1 and of the drum d has the tendency to move forward 20 and downward (position shown in dotted lines in Figs. 7); the drum d rubs against the band d^2 , and the roller a^1 is braked, so that a point of support is thus obtained on the ground in order to communicate an 25 impulse to the apparatus.

This arrangement has the advantage that for turning, the roller a^1 can rotate backward as long as a sufficient effort is not exercised on the skate in order to shift the 30 eccentric trunnion d^1 in its bearing.

Obviously, the invention is not limited to the construction described and illustrated; for instance, in place of a rigid frame b , may be used a pivoted parallelogram, on two parallel sides of which move the roller skates. 35

Instead of moving parallel to each other, the two skates a might be forced to follow given curves, for instance curves of a small radius, corresponding to the movement of 40 the feet in walking. It is also possible to use any other free wheel device differing from those described and illustrated.

The apparatus according to this invention may be combined with any vehicles, for instance with a three wheel vehicle; the trailer 45 will constitute in this case the steering part.

I declare that what I claim is:

1. In a device of the general character de-

scribed, a frame, a steering wheel connected thereto, a longitudinally displaceable foot 50 support guided by said frame, a bearing roller associated with said foot support, and means for holding said roller against rotation in one direction.

2. In a device of the general character described, a frame, a steering wheel connected thereto, a longitudinally displaceable foot support guided by said frame, a bearing roller associated with said foot support, and means for holding said roller against rotation in one direction, together with means for rendering said holding means temporarily inoperative.

3. In a device of the general character described, a frame having longitudinally extending side members, a steering wheel jointed to the frame, a foot support freely engaging one of said side members of the frame, a bearing roller associated with said foot support, and means for holding said roller against rotation in one direction.

4. In a device of the general character described, a frame having a pair of longitudinally extending side members spaced apart, a steering wheel pivoted to the frame, a pair of foot supports respectively freely engaging said side members, bearing rollers associated with each of said foot supports, and means for holding the roller of one of said foot supports against rotation in one direction.

5. In a device of the character described, a foot support, a roller, a bearing spindle associated therewith, an eccentric on said spindle, a bearing on said foot support in which said eccentric is mounted, in combination with a brake device for the wheel operative upon the rotation of said eccentric in its bearing.

In testimony whereof I have signed my name to this specification.

AUGUSTE RENÉ LUCAS.
